UNITED STATES PATENT OFFICE.

CARL SCHÜRMANN, OF DUSSELDORF, GERMANY.

MANUFACTURE OF BRAIDED CORDS OR CABLES FOR ELECTRIC LIGHTING OR LIKE PURPOSES.

SPECIFICATION forming part of Letters Patent No. 703,837, dated July 1, 1902.

Application filed December 24, 1900. Serial No. 40,946. (No model.)

To all whom it may concern:

Be it known that I, CARL SCHÜRMANN, a subject of the Emperor of Germany, residing at Dusseldorf, Germany, have invented 5 certain new and useful Improvements in the Manufacture of Braided Cords or Cables for Electric Lighting and Like Purposes, of which the following is a specification.

In the drawings, Figures 1 and 1^a are cross-10 sectional views showing the manner of braiding the conductors with and without the central core. Fig. 1^b shows in cross-section a common manner of placing the cords on the conductor. Figs. 2 and 3 are views corresponding to Fig. 1, showing different ways 15 of applying three cords to as many conductors. Fig. 3^a is a similar view, on a reduced scale, corresponding to Fig. 1^a, but showing the three-cord procedure; and Fig. 3^b shows 20 in cross-section a well-known manner of placing the cords on the conductors. Fig. 4 shows in side elevation a cord of the kind represented in Fig. 1^a.

Like characters refer to like parts in all 25 the figures of the drawings.

This invention relates to the manufacture 30 of braided cords or cables for electric lighting and like purposes; and it consists, essentially, in that the several wires or conductors required for the manufacture of the cords, &c., are united or connected together by the braid 35 in the process of braiding the separate wires and can, if desired, be also laid or twisted together for the purpose of increasing the speed of braiding by reducing the number of steps heretofore employed in the manufacture thereof and of diminishing the risk of short-circuiting.

My invention is illustrated in the accompanying drawings, in which the braided and connected wires or conductors are shown in cross-section.

Figs. 1 and 1^a show the new method applied to the braiding of electric-light cords 40 with two conductors, with and without a carrier or insulation core, respectively. The copper wires or conductors A and B, which are first covered with india-rubber strip and cotton, are then braided simultaneously by 45 two systems of threads d and e, which may differ externally in color in such a manner that the color system d only moves around the

wire A and the insulation or carrier core T, while the color system e only moves around the wire B and around the carrier-core T, in 55 which operation the systems d and e cross each other and are thus connected together. When unnecessary, the insulation -core T, which runs straight along the axis, can obviously be dispensed with, Fig. 1^a. 60

Fig. 4 shows in side elevation an example of the cord shown in Fig. 1^a. In this cord the light braiding-threads d' d², passing spirally around the core A, interloop with those e' e², 65 passing spirally around the core B, this interlooping being indicated by dotted lines. The cores A B are, moreover, laid or twisted around each other in a similar manner to the flexible electric-light cords heretofore employed. 70

With cords having three conductors two methods of interweaving, Figs. 2 and 3, are possible according to my invention. In Fig. 2 each wire or conductor is only covered by one system of threads. Thus A by d only, B 75 by e only, C by f only. These three systems of threads, however, cross and interlock with each other in the center. In Fig. 3, on the other hand, each single wire or conductor is braided by two systems of threads, which also 80 cross each other and interlock. Thus A is braided by d and f, B by e and d, C by e and f. In three-conductor cables of this kind the insulation or carrier core T can also be dispensed with, if desired, Fig. 3^a. 85

In the methods heretofore employed for the manufacture of electric-light cords, &c., each single core is braided all around by itself, and the braided cores are afterward laid or twisted together to unite them, Fig. 1^b. A cable 90 of this kind has thus no special insulating or carrier core, and consequently does not nearly present the security against short-circuiting possessed by a cable made as shown in Fig. 1. If a carrier-core be employed, (for supporting the incandescent lamp, &c.,) one is 95 compelled with the methods heretofore employed to braid this insulating carrier-core by itself and then to lay or twist it together with the two other copper wires or cores, Fig. 100 3^b. Obviously the carrier-core has to follow the spiral rotation of the copper cores or wires, and it cannot therefore be determined what load is effectively taken by the carrier-

core. Moreover, by using a carrier-core according to the methods heretofore employed the risk of short-circuiting is not reduced, since the small distance apart of the inner 5 copper wires from each other remains the same. According to my new method, Fig. 1, this distance is equal to the diameter of the insulation-core plus double the thickness of the braiding and of the internal covering.

10 o What I claim is—

15 1. A method of covering a plurality of conductors and a central core for electric-light cords, consisting in braiding a system of covering-threads around each conductor and the central core, and simultaneously interlooping the threads of the several systems, substantially as described.

20 2. A method of covering a plurality of conductors and a central core for electric-light cords, consisting in arranging the conductors in groups, braiding a system of covering-threads around each group and the central

core, and simultaneously interlooping the threads of the several systems, substantially as described.

25 3. A plurality of conductors, a core, systems of threads, each system braided around a conductor and the core and interlooped with the other systems between said conductors, substantially as described.

30 4. A plurality of conductors arranged in groups, a core, and systems of threads, each system braided around a conductor and the core and interlooped with the other systems between said conductors, substantially as de- 35 scribed.

In testimony whereof I have hereunto set my hand in presence of two subscribing witnesses.

CARL SCHÜRMANN.
